UNITED STATES PATENT OFFICE.

FREDERICK W. GEHRKE, OF WEST COLLINGSWOOD, NEW JERSEY, ASSIGNOR TO THE HORN AND BRANNEN MANUFACTURING COMPANY, OF PHILADELPHIA, PENNSYLVANIA, A CORPORATION OF PENNSYLVANIA.

DESIGN FOR A SHELL FOR GAS OR ELECTRIC-LIGHT FIXTURES.

42,963.

Specification for Design.

Patented Sept. 3, 1912.

Application filed June 14, 1912. Serial No. 703,750. Term of patent 7 years.

To all whom it may concern:

Be it known that I, FREDERICK W. GEHRKE, a citizen of the United States, residing in West Collingswood, county of Camden, State of New Jersey, have invented a certain new, original, and ornamental Design for Ornamental Shells for Gas or Electric-Light Fixtures, of which the following is a specification, reference being had to the accompanying drawing, forming part thereof.

The figure is a perspective view of an ornamental shell for a side wall gas or electric light fixture, showing my new design.

I claim:

The ornamental design for a shell for a gas or electric light fixture, as shown.

FREDERICK W. GEHRKE.

Witnesses:

A. M. BIDDLE,
R. A. DUNLAP.
